UNITED STATES PATENT OFFICE.

EDWARD H. HORSTKOTTE, OF SCHENECTADY, NEW YORK, ASSIGNOR TO GENERAL ELECTRIC COMPANY, A CORPORATION OF NEW YORK.

CONTROL OF ARCING ELECTRODES.

Application filed October 14, 1921. Serial No. 507,706.

To all whom it may concern:

Be it known that I, EDWARD H. HORSTKOTTE, a citizen of the United States, residing at Schenectady, in the county of Schenectady, State of New York, have invented certain new and useful Improvements in Control of Arcing Electrodes, of which the following is a specification.

My invention relates to an improved control for arcing electrodes. Although the invention is particularly useful in the control of the arcing electrodes of an electric furnace, the invention is not necessarily limited to the control of furnace electrodes, but may also be used in the control of other electric translating devices as well.

In prior electrode control arrangements, electromagnetic switch mechanism has been provided for controlling the arcing relation of the electrodes and the switch mechanism has been automatically operated to effect the control of the electrodes in response to a condition of the arcs supported by the electrodes. Due to the self-induction of switch electromagnets and the mechanical inertia of the movable elements of the switches, the control of the electrodes has been tardy and there is also a tendency 30 to cause overrunning. Electroresponsive means such as electric motors have heretofore been provided for regulating the electrodes under the control of the said electromagnetic switch mechanism, and the inertia and self-induction of the motors has been added to the tardy effect and the tendency to overrunning.

One of the objects of the invention is to eliminate the electromagnetic switch mechanism heretofore provided, in arrangements for controlling electrodes and other translating devices, and to minimize the tardy effect and the tendency to overrunning, so that the electrode or other translating device will be governed practically simultaneously with the occurrence of the electrical condition or conditions which make desirable the control of the electrode or other translating device.

In carrying my invention into effect as applied to the control of the arcing electrodes of an electric furnace, I provide an electric valve for controlling the arcing relation of the electrode. The electric valve may be of an electron discharge type, such

for instance as a headed cathode rectifier, commonly called a kenetron. The valve or electron discharge device is electrically connected to the arcing electrode so as to be responsive to the electrical condition or 60 conditions of the arc supported by the electrode, so that the regulating effect of the valve is practically simultaneous with the occurrence of the electrical condition which makes necessary a regulation of the electrode. In the embodiment of my invention which I have selected for purposes of illustration, the electric valve controls the energization of an electrode motor by controlling the energization of a generator 70 supplying current to the motor, and although the arrangement which I have thus selected has certain important advantages, I conceive that the broad features of the invention can be carried out by other 75 means.

For a better understanding of the invention, reference is had to the accompanying drawing in which I have shown for purposes of illustration the particular embodiment of the invention above referred to. Referring to the drawing, the electric translating devices controlled comprise the electrodes 10, 11 and 12 which are suspended over the bath in an electric furnace 13. 80 These cooperating electrodes are adapted to support arcs for heating the bath contained in the furnace. The separately excited direct current motors 14, 15 and 16 are provided as the electroresponsive means for 85 controlling the arcing relation of the electrodes 10, 11 and 12 respectively. The energization of these electrode motors is controlled by means comprising the electric valves 17, 18 and 19 respectively. The electric valves shown are of the electron discharge type, in which a hot cathode 20 cooperates with the plate or anode 21 within a container 22. A hot cathode electron discharge device such as a kenetron is satisfactory for the purposes of my invention.

The electric valves are connected so as to be responsive to the electrical condition of the arc supported by the electrode controlled by the valve. Thus, the valve may be responsive to the flow of current in the circuit of the electrode controlled thereby, and for controlling the electrode in response to this electrical condition, I have provided current transformers 23, 24 and 25 for the valves 110

17, 18 and 19 respectively, and connect the secondary of each current transformer to its respective valve, so that the plate current will vary approximately proportional to the 5 voltage on the secondary of the series transformer and thus vary in accordance with the current in the arcing electrode circuit. The hot cathode of each valve is connected across all or a portion of the secondary 10 winding of its respective current transformer. Thus, for example, the hot cathode 20 is connected across a portion of the secondary windings of the current transformer 23, and a resistor 26 is included in 15 the hot cathode circuit so as to regulate the heating effect and thereby the current in the plate circuit. By means of the resistors included in the hot cathode circuits of the electric valves, the operation of each electrode 20 motor may be adjusted with respect to the other electrode motors, so that after having been adjusted, the electrode motors will be caused to cooperate to regulate their respective electrodes in the manner desired. 25 Instead of employing the plate current of a valve or rectifier to directly control its respective electrode motor, I prefer to control the electrode motors by controlling the energization of separately excited direct 30 current generators 27, 28 and 29, each having its armature directly connected to supply the current for the armature of its respective electrode motor. These generators may all be mounted on one shaft and be 35 driven by an alternating current motor 30 energized from the source of supply 31 through the transformer 32, to which the furnace electrodes are also connected. Each of these generators is provided with a field 40 winding supplied with current from an exciter 33 mounted on the shaft of the alternating current driving motor 30 so as to be driven therefrom. The exciter also supplies the current for the separately excited fields 45 of the electrode motors. The generator 27 is provided with a shunt field 34 which is energized by the plate current of the rectifier 17, and this shunt field 34 is differentially wound with respect to the shunt field 35 of the generator. The generators 28 and 29 are provided with similar fields and are controlled in a similar manner. The arrangement is such that when the current in the 50 circuit of the electrode 10 is substantially normal, the two fields 34 and 35 substantially neutralize each other so that the voltage supplied to the armature of the electrode motor 14 is practically zero value, but in case the current should either increase 55 or decrease from the predetermined normal, the value of the voltage and the direction of the current supplied to the armature of the electrode motor 14 will be such that the motor will be caused to practically simultaneously operate the electrode 10 to such a

position that the condition in the arc circuit of the electrode is automatically and quickly brought back to normal.

As thus constructed and arranged, the operation of my invention is as follows: 75 Assume that the equipment is operating and that the resistors in the cathode circuits of the rectifiers have been properly adjusted, the value of current supplied to the separately excited fields of the generators and 80 the value of current supplied to the separately excited fields of the motors from the exciter 23 have been adjusted so that a normal condition of the arcing relation of the electrodes has been established, and that it is desired that this normal relation be maintained. Assume that the current in the circuit of the electrode 10 increases above the predetermined value. The voltage induced in the secondary of the transformer 85 23 will be correspondingly increased and the heating effect of the cathode 20 of the rectifier 17 will also be correspondingly increased. The plate current of the rectifier will thereby be correspondingly increased, so that the current in the field winding 34 of the generator 27 will also be increased. This will destroy the balance between the separately excited field 35 and the field 90 winding 34, the field winding 34 will now 95 predominate, thereby causing the generator 27 to build up practically simultaneously a voltage corresponding in value and direction to the increase in the current of the circuit of the electrode 10. The armature of the electrode motor 14 will be simultaneously energized to operate the electrode 10 to raise the electrode until the value of the current in the electrode circuit becomes the normal value which it is desired shall be maintained. 100 105

In case the current in the electrode circuit decreases below the predetermined normal value, the cathode 20 will be heated to a correspondingly less value, the energization of the field winding 34 will be correspondingly decreased, and the field winding 35 of the generator 27 will now predominate to reverse the current supplied by the generator to thereby cause the motor 13 to lower 110 115 the electrode 10 until a stable condition is restored.

It will be apparent from the above that the entire arrangement is very sensitive to changes in the electrical conditions of the 120 arc supported by the electrodes. The adjustment of the electrodes is effected substantially coincidentally with the occurrence of the electrical condition which makes necessary an adjustment of the electrodes. 125 It will also be observed that the electrode motors are prevented from overrunning, since the motors will operate in each direction to a limit determined by the value of the voltage induced in the secondary of 130

the corresponding current transformer. Furthermore, the motors will operate as regenerative braking generators returning energy to the supply circuit in case the generated voltage of the motor should at any time be greater than the voltage of its respective generator.

It will be understood by those skilled in the art that the electrical condition of the arc supported by one of the arcing electrodes has an effect on the electrical condition of the arcs supported by the other electrodes of the furnace, so that the adjustment of one electrode will be accompanied by the practically simultaneous adjustment of the other electrodes in case the adjustment of one electrode makes necessary the adjustment of the other electrodes to restore the normal condition initially determined upon.

20 It will be observed that since the energy supplied to the furnace electrodes and the energy for driving the electrode motors is all taken from the source of supply 31, a failure of said source will not cause the electrodes to be lowered into the furnace bath.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. The combination with an electrode adapted to support an arc, of means comprising an electric valve for regulating the arcing relation of the said electrode, and connections whereby the said valve regulates the arcing relation of said electrode in accordance with an electrical condition of the arc supported by said electrode.

2. The combination with an electrode adapted to support an arc, of an electric valve connected to be responsive to an electrical condition of the arc supported by said electrode, and electro-responsive means controlled by said valve for regulating the arcing relation of the said electrode.

3. The combination with an electrode adapted to support an arc, of means comprising an electric valve for regulating the arcing relation of the said electrode, and connections whereby the said valve regulates the arcing relation of said electrode in accordance with the current in the arc supported by the electrode.

4. The combination with an electrode adapted to support an arc, of means comprising an electron discharge device for regulating the arcing relation of the said electrode, a current transformer having its

primary in the circuit of said electrode and its secondary connected to the said device, and means controlled by the said device for regulating the arcing relation of said electrode.

5. The combination with an electrode adapted to support an arc, of an electric motor for controlling the arcing relation of said electrode, an electron discharge device for controlling the said motor, and connections whereby the said device controls the operation of said motor in accordance with the conditions in the circuit in which said electrode is included.

6. The combination with an electrode adapted to support an arc, of an electric motor for controlling the arcing relation of said electrode, an electron discharge device for controlling the said motor, and connections whereby the said device controls the operation of said motor in accordance with the current in the arc supported by the said electrode.

7. The combination with an electrode adapted to support an arc, of an electric motor for controlling the arcing relation of said electrode, an electron discharge device and connections whereby said device controls the direction and the limit of operation of said motor in accordance with conditions in the circuit in which the said electrode is included.

8. The combination with an electrode adapted to support an arc, of an electric motor having a field and an armature controlling the arcing relation of said electrode, an electron discharge device, and connections whereby the said device controls the relative direction of the field and armature currents of said motor responsive to a condition of the arcing circuit of said electrode.

9. The combination with an electrode adapted to support an arc, of an electric motor for controlling the arcing relation of said electrode, a generator for supplying current to the said motor, an electron discharge device and connections whereby the said device controls the current supplied by the said generator to the said motor in accordance with a condition of the arcing circuit of the said electrode.

10. The combination with an electrode adapted to support an arc, of an electric motor for controlling the arcing relation of said electrode, a generator for supplying current to the said motor, an electron discharge device, and connections whereby the said device controls the voltage and the direction of current supplied by the said generator to the said motor in accordance with a condition of the arcing circuit of said electrode.

11. The combination with an electrode adapted to support an arc, of a separately

excited motor for controlling the arcing relation of said electrode, a separately excited generator for supplying the current to the armature of said motor, an electron discharge device and connections whereby the said device controls the voltage and the direction of current supplied by the said generator to the said motor in accordance with the currents passing through the said electrode.

12. The combination with an alternating current supply circuit, of an electric translating device connected to be supplied with current from the said supply circuit, an electric motor for regulating the said device, an electron discharge device, and connections whereby the said electron discharge device controls the direction and the limit of operation of the said motor in accordance with a condition of the supply of energy to the said translating device.

13. The combination with an alternating current supply circuit, of an electric translating device connected to be supplied with current from the said supply circuit, a direct current motor for regulating the said device, a heated cathode electron discharge device, and connections whereby the said electron discharge device controls the energization of the said motor in accordance with the current taken by the said translating device.

14. The combination with an alternating current supply circuit, of an electric translating device connected to be supplied with current from the said supply circuit, a direct current motor for regulating the said device, a direct current generator connected to supply the current for the said motor, a heated cathode electron discharge device, and connections whereby the said electron discharge device controls the voltage and the direction of current supplied by the said generator to the said motor in accordance with the current taken by the said translating device.

15. A regulator for an electric arc furnace having a plurality of cooperating electrodes connected to an alternating current supply circuit, comprising a separate direct current motor for regulating the arcing relation of each electrode, a separate direct current generator for supplying the current to each of said electric motors, a separate heated cathode electron discharge device for controlling each of said generators, and connections whereby the said devices control their respective generators in accordance with the current passing through their respective electrodes.

In witness whereof, I have hereunto set my hand this 13th day of October, 1921.

EDWARD H. HORSTKOTTE.
